WARP BEAM

Heinz Menking, Rocky River, Ohio, assignor to
 Aluminum Company of America, Pittsburgh,
 Pa., a corporation of Pennsylvania

Application October 25, 1944, Serial No. 560,273

5 Claims. (CL 242—124)

1

This invention relates to metal warp beams and has particular reference to those made of light metals such as magnesium or magnesium base alloys.

Warp beams, as understood by those skilled in the art, refer to the large spools used in weaving mills, being filled in warpers with yarn from creels and discharged in the slasher, from where the yarn is rewound on loom beams or discharged directly onto loom beams. A form of warp beam known as section beams is also employed as a convenient shipping holder for tire cord yarn from which the yarn is distributed to the twisters. Another type of warp beam, also known as tricot warp spool, is used in the warp knitting industry and for shipment of rayon yarn to the knitting mills. These beams for many years have been made of wood because of the relatively light weight of this material and the ease with which it can be shaped. With increasing demands for speed and precision in operation and with the introduction of finer and more delicate textile fibers, it has been found that the wooden beams are inadequate from the standpoint of strength, stiffness, and permanence of dimensions. Furthermore, in loading a beam, some synthetic yarns stretch elastically under the tension applied to them with the result that a great crushing force is exerted on the barrel of the beam after the yarn has been wound upon it. Also, some yarns exert a high pressure on the heads of the beams, this pressure being sufficient in some cases to deform, if not break, the heads if the beams are nearly or completely filled. For this reason wooden beams can only be partially filled with such synthetic yarns in general practice. Moreover, the wooden beams are subject to warpage, cracking, and splintering under the temperature and humidity conditions encountered in textile mills. The deformation induced by the yarn load and the natural warpage of the wood is especially objectionable because it destroys the initial dynamic balance of the beams with resultant adverse effect upon their quality and speed and damage to yarn and the whole machine.

Attempts have been made to overcome the foregoing deficiencies by reinforcing the wooden beams or substituting metal for the wood as structural material. While reinforcement of the wooden beams has increased their strength, it has not eliminated the inherent deficiencies of wood mentioned above. On the other hand, metal beams substituted for the wooden products have possessed greater dimensional stability

but have been either too heavy for high speed operation or have had certain structural features which led to premature failure. Furthermore, they have not been well adapted to high speed operation such as now often obtains in the industry, for example, warping speeds of 1000 yds./min. are not uncommon, whereas in the past the speed was only 150-250 yds./min. If used at such high speeds, such wooden or metal beams develop bad vibrations.

One of the particular defects associated with the construction and performance of warp beams, especially section beams, has been the problem of providing a light weight, yet strong, joint between the barrel and the beam heads. One of the common constructions employed in making small metal beams has been to use cast heads having an annular flange or collar extending inwardly over which the beam barrel is pressed or telescoped, and the two parts are riveted, bolted, or welded together. This arrangement on a large beam, however, is open to the objection that an integrally cast collar on the head gives rise to a concentration of stresses at the place where the collar joins the head, and failure at this point sometimes occurs. To overcome this deficiency in strength, it would be necessary to increase the thickness of the collar and enlarge the fillets between the collar and the head, thus increasing the weight of the beam. Furthermore, with the integrally cast collar construction it is difficult to obtain a very tight joint between the heads and the barrel where this is necessary or desirable. In other designs of beams no collar of any kind is provided, the heads being directly attached to the barrel by bolts or other suitable mechanical means. With the foregoing deficiencies of beams in mind, I have devised a new type of joint which is easy to form and maintain.

One of the primary objects of my invention is to provide a metal warp beam in which the joint between the heads and barrel is strong, tight, and light of weight. A further object is to provide a joint between the heads and barrel of a warp beam which can be easily made in commercial production. Still another object is to provide a light, strong warp beam made of a light metal, especially magnesium base alloys. Yet another object is to minimize harmful concentration of stress between the barrel and the heads. A particular object is to provide a light metal section beam in which the heads can be drawn up against the barrel to form a tight joint

leaving no crevice in which the yarn might be caught.

With these and other objects in view, the invention consists of certain novel features of construction, as will be more fully described and particularly pointed out below and in the appended claims.

In the accompanying drawings showing a preferred form of my invention:

Fig. 1 is a side elevation, partially in section, 10 of a complete section beam;

Fig. 2 is a cross section on line II—II of Fig. 1; and

Fig. 3 is an enlarged sectional view of the joint between the head and barrel section of a beam 15 on line III—III of Fig. 2.

The beam illustrated in Fig. 1, consists essentially of the heads 1 joined to a barrel 17 through the medium of a collar 20 at each end of the barrel. The heads and collar may be made conveniently in cast form while the barrel may be an extrusion. The heads consist of a disc portion having a peripheral flange 3 preferably protected against injury and wear by a band of a harder metal 5, such as iron. The head has radial ribs 7 uniformly spaced about the head, extending from the central portion thereof to the peripheral flange 3, and ribs 8 extending from said portion to the hub 9 on the opposite side of the head. The steel shaft 11, held in place by nuts, supports the beam when in use, but is not relied upon to hold the heads against the barrel. This shaft may be replaced by a separate stub shaft or gudgeon pin in each head. Holes 13 are provided in the heads a short distance from the hub through which pass stud bolts 15 that carry nuts for securing the heads to the collars 20 which are positioned at each end of the barrel. Any suitable magnesium base alloys may be employed for making the heads, collar, and barrel, a satisfactory casting alloy being one nominally containing 9 per cent aluminum, 2 per cent zinc, and 0.2 per cent manganese. Castings made of this composition should receive a conventional heat treatment and be quenched in known manner to develop a high strength. An alloy adapted for extrusion is one which nominally contains 3 per cent aluminum, 1 per cent zinc, and 0.2 per cent manganese.

To provide an accurate fit between barrel and collars the interior of barrel 17 is preferably machined inwardly of the ends thereof to form a uniform reduced section 19, which gradually increases to the full wall thickness of the barrel, to accommodate the collar 20 and facilitate its attachment thereto. Where the interior of the barrel is thus machined, it is preferable that the reduced section be of uniform thickness for a short distance inwardly of the barrel ends and that the wall thickness gradually increase beyond said reduced section to the full wall thickness of the barrel. The ends of the barrel are also machined and are preferably beveled outwardly from the internal to the external diameters, thus providing beveled surface 33, as shown in Fig. 3. In this figure the acute angle formed by beveling the end of the barrel provides a line contact 31 with the barrel head when they are drawn together. This construction is of particular value where a very tight joint is desired such as that required when certain very fine synthetic yarns are wound upon the beam.

The heads are joined to the barrel portion of the beam through collars 20, as mentioned hereinabove. The collar, preferably in the form of

a casting made of the same alloy as the heads, has internal reinforcing ribs 23 symmetrically spaced around said collar and parallel to the axis of the barrel with intervening valley sections 22 between the ribs, as is more clearly shown in Fig. 2, the ribs being properly proportioned to provide an anchorage for stud bolts 15 in holes 25. The ribs also strengthen the ends of the barrel and thereby increase its load bearing capacity. The collar 20 preferably extends into the barrel past the uniform reduced section 19 with a suitably tapered contour to correspond to the transition in wall thickness of the barrel from the reduced to the full section, and thus provide ample reinforcement of the barrel near the ends. The ribs do not extend over the full length of the collar but they and the valleys merge into a solid ring 21 at the inner end of the collar. The ribs do, however, extend over a substantial length of the collar. The collar 20 may be attached to the barrel by spot welds 27 in the valley sections 22 intermediate the ribs 23. The reduced thickness of the collar in the valley sections makes it possible to easily weld or rivet it to the barrel. To avoid any buckling or bending of the barrel as it is drawn up to the head, it is highly desirable to have the barrel secured to the collar close to the end of the said barrel. Also to avoid possible interference with obtaining a tight joint between the barrel ends and the heads, the collars should be spaced slightly inwardly of the ends of the barrel. One of the important advantages of the rib and valley construction of the collar described above is the smaller weight of such a member as compared to the weight of a solid metal ring of uniform wall thickness and thick enough to provide adequate anchorage for the stud bolts. Such a saving in weight in the ribbed collar is of particular value in the manufacture of light weight section beams.

In assembling the beam, the collars 20 are first secured to the previously machined barrel 17 and stud bolts 15 put in place. The heads are then mounted on the barrel assembly and drawn up by nuts on the stud bolts to make a tight line contact 31 between the barrel and the heads. As clearly shown in Fig. 3, the collar 20 does not come in contact with the head in the assembled construction but a space 28 is left between them. By providing this space 28, sufficient clearance is allowed for drawing the beveled barrel ends against the heads and form a line contact therewith.

It has been found that beams made in accordance with the foregoing construction can be completely filled with synthetic yarns without failure at the joint between the barrel and the head, and without distortion. It will also be appreciated that this construction permits convenient disassembly of heads and barrel for maintenance purposes.

While one embodiment of my invention has been described above, it will be appreciated that other designs may be made which embrace the principles of my invention and which produce the same result.

Having thus described my invention, I claim:

1. A metal warp beam comprising two heads, a barrel portion, and a collar member having integral internal solid ribs therein positioned at each end of the barrel and in the interior thereof and rigidly secured both to the adjacent head and to the barrel, the internal solid ribs of said collars being parallel to the axis of the barrel and

extending over a substantial portion of the length of the collar, said solid ribs also having threaded openings therein to receive screw fastening means for securing said heads to said collars.

2. A metal warp beam comprising two heads, a barrel portion, and a collar member having integral internal solid ribs therein positioned at each end of the barrel and in the interior thereof and rigidly secured both to the adjacent head and to the barrel, the internal solid ribs of said collar members being parallel to the axis of the barrel and extending over substantially the entire length of the collar, and the barrel being rigidly secured to the collar members at the valleys between the internal ribs thereon, and the heads being secured to the said collars by screw means anchoring in threaded openings in the said internal solid ribs.

3. A metal warp beam comprising two heads, a barrel portion, and a collar member having integral internal solid ribs therein positioned at each end of the barrel and in the interior thereof and rigidly secured both to the adjacent head and to the barrel, the internal solid ribs of said collar being parallel to the axis of the barrel and extending over a substantial portion but not the entire length of the collar and merging into a solid ring at the end of the collar opposite to that secured to the beam head, said solid ribs also having threaded openings therein to receive screw fastening means for securing said heads to said collars.

4. A metal warp beam comprising two heads, a barrel portion, and a collar member having integral internal solid ribs therein positioned at each end of the barrel and in the interior thereof and rigidly secured both to the adjacent head and to the barrel, the internal solid ribs of said collar members being parallel to the axis of the barrel and extending over substantially the entire length of the collar, the ends of the barrel having a section of uniform reduced wall thickness for a short distance inwardly of the ends thereof that

gradually increases to the full wall thickness of the barrel inwardly of said section, and the collar members having a length at least equal to that of the section having a reduced wall thickness, the barrel being rigidly secured to the collar members at the valleys between the said internal ribs and the heads being secured to said collars by screw means anchoring in the said internal solid ribs.

5. A metal warp beam comprising two heads, a barrel portion, and a collar member having integral internal solid ribs therein positioned at each end of the barrel and in the interior thereof and rigidly secured both to the adjacent head and to the barrel, the internal solid ribs of said collar members being parallel to the axis of the barrel and extending over a substantial portion but not the entire length of the collar, and merging into a solid ring at the end of the collar opposite to that secured to the beam head, the ends of the barrel having a uniform reduced wall thickness for a short distance inwardly of the ends thereof that gradually increases to the full wall thickness of the barrel inwardly of said section, and the collar members having a length at least equal to that of the section having a reduced wall thickness, the barrel being rigidly secured to the collar members at the valleys between the said internal ribs and the heads being secured to said collars by screw means anchoring in the said internal solid ribs.
